Specification for Design.

Patented Jan. 25, 1921.

Application filed October 16, 1919. Serial No. 331,195. Term of patent 3½ years.

To all whom it may concern:

Be it known that I, MARK B. NELSON, a citizen of the United States, residing at Los Angeles, in the county of Los Angeles and State of California, have invented a new, original, and ornamental Design for Children's Coasters, of which the following is a specification, reference being had to the accompanying drawing, forming a part thereof.

Fig. 2 is a side elevation of a child's coaster showing my new design.

I claim:

The ornamental design for a child's coaster as shown.

MARK B. NELSON.
